NUTCRACKER

Willie Erwin Pricer, Galveston, Tex.

Application February 13, 1941, Serial No. 378,804

2 Claims. (Cl. 146—16)

This invention relates to an improved nut cracker of simple construction capable of being economically manufactured and sold and which may be operated with very little effort or force on the part of the operator.

More particularly, it is an aim of the invention to provide a nut cracker having a lever type operator for urging the jaws to a closed position and which is of sufficient length to provide ample leverage so that the jaws can be closed with very little force applied to the free, handle end of the lever.

Still another aim of the invention is to provide a nut cracker of the above described character wherein the jaws can be closed very gradually or slowly so that when the shell of a nut disposed between the jaws is cracked the closing movement of the lever can be stopped so that the nut will not be crushed between the jaws.

Other objects and advantages of the invention will hereinafter become more fully apparent from the following description of the drawing, which illustrates a preferred embodiment thereof, and wherein—

Figure 1 is a side elevational view of the nut cracker, showing the jaws in a closed position.

Figure 2 is a fragmentary side elevational view of the same, showing the jaws in an open position.

Figure 3 is an end view in elevation of the nut cracker looking toward the forward end thereof.

Figure 4 is a transverse sectional view taken substantially along the plane of the line 4—4 of Figure 1, and

Figures 5 and 6 are enlarged cross sectional views taken substantially along the planes of the lines 5—5 and 6—6, respectively, of Figure 1.

Referring more particularly to the drawing, wherein like reference characters designate like or corresponding parts throughout the different views, 10 designates generally the improved nut cracker comprising the invention and which includes a base or supporting stand 11. An elongated jaw 12 is disposed lengthwise of the base 11 and extends beyond the forward end thereof and is secured thereto by means of bolts or other threaded fastenings 13 which extend downwardly through the parts 11 and 12. The heads of the bolts 13 are countersunk in the upper face 14 of the jaw 12. A U-shaped bracket 15 has its intermediate portion countersunk in the face 14, adjacent the rear end of the jaw 12, and said intermediate portion is engaged by one of the

fastenings 13, as best seen in Figure 5, for connecting the bracket 15 to the jaw 12.

A movable jaw 16 is disposed above the jaw 12 and substantially co-extensive therewith and has a portion thereof extending through and disposed between the upset legs 17 of the bracket 15. The legs 17 are provided with aligned apertures 18 and the jaw 16 is provided with a transverse bore 19 which registers with the apertures 18 for receiving the shank of the bolt of a nut and bolt fastening 20 by means of which the jaw 16 is pivotally connected to the jaw 12 adjacent the rear ends of the jaws. The upper side of the jaw 16 is inclined downwardly from the point 21, adjacent its forward end, to its rear end, for a purpose which will hereinafter become apparent, and the upper engaging face 14 of the jaw 12 is inclined downwardly beyond the bracket 15 toward its rear end to form the inclined surface 22. The under side of the rear end of the jaw 12 is notched at 23 to engage a portion of an elastic band 24 which engages over the tapered rear end of the jaw 16 for urging said end downwardly and for causing the opposite end of the jaw 16 to be moved upwardly to an open position, as seen in Figure 2. The jaw 12 is provided with the inclined surface 22 to accommodate the rear end of the jaw 16 when said jaw is in an open position.

The jaw 16 is provided with an engaging face 25 disposed in opposed relationship to the face 14. The faces 14 and 25 and the sides of the jaws 12 and 16, adjacent their forward ends, are recessed at 26 to receive inserts 27 which are countersunk therein and which are of corresponding shape and construction. The inserts 27 are preferably formed of a hardened metal and are secured to the jaws 12 and 16 by fastenings 28 which engage the flanges 29 thereof, as best seen in Figure 6. Said inserts 27 are provided with opposed cup shaped recesses 30 which are adapted to receive the end of a nut, not shown, which is disposed between the forward ends of the jaws 12 and 16.

A rod 31, as best seen in Figures 3 and 4, is provided with corresponding ends 32 which are disposed at right angles to its intermediate portion and which extend in the same direction. One of the ends 32 is journaled in the jaw 12, adjacent its forward end, and the other end 32 is journaled in a lever 33 adjacent one end thereof. Said end of the lever 33 is enlarged and provided with a curved surface 34 which is eccentrically disposed relatively to the transverse bore 35 in which said last mentioned end 32 is jour-

naled. An elongated link 36 engages the ends 32, adjacent their extremities, and the extremities of the ends 32 are provided with heads 37 to prevent detachment of the link 36 which in turn prevents detachment of the ends 32 from the jaw 12 and lever 33. The upper surface of the jaw 16 slopes downwardly from the point 21 to its forward end to form a cam surface 38 which is adapted to be engaged by the eccentric surface 34. The lever 33 tapers towards its opposite, free end which is curved to form a handle portion 39.

Assuming the handle end 39 of the lever 33 to be in a raised position, the elastic member 24 will hold the jaw 16 elevated, as seen in Figure 2, to retain the lever 33 in substantially an upright position. With the jaws thus disposed, a nut to be cracked may be readily inserted between the forward ends of the jaws and the ends of the nut positioned in the recesses 30. The handle 39 is then swung downwardly and rearwardly relatively to the jaws 12 and 16 to cause the surface 34 to ride over the cam surface 38 for forcing the forward end of the jaw 16 to swing downwardly on its pivot 20. When the jaws are in a fully closed position, the lever 33 will be disposed above and adjacent the jaw 16 with its handle end 39 extending substantially beyond the rear end thereof. Due to the fact that the lever 33 engages the jaw 16 adjacent its forward end and remote to its fulcrum point substantial leverage will be thereby afforded by the jaw 16 and as the lever 33 is of a substantial length and pivoted at one end thereof very little force will be necessary to move the free end 39 of the lever 33 due to the leverage afforded thereby. Consequently, the combined leverage afforded by the jaw 16 and the lever 33 will permit the nut cracker 10 to be operated with very little force exerted on the end 39 so that the movable jaw 16 can be swung toward the stationary jaw 12 with a slow, steady movement and consequently when the nut, which is disposed between the jaws is cracked the movement of the lever can be stopped to prevent the jaws

from fully closing and crushing the nut. It will be obvious that the rod 31 pivotally mounts the lever 33 and also swingably mounts said lever relatively to the stationary jaw 12 so that it is capable of two swinging movements relatively to the jaws.

Various modifications and changes are contemplated and may obviously be resorted to as only a preferred embodiment of the invention 10 has been disclosed.

I claim as my invention:

1. A nut cracker comprising an elongated stationary jaw having an upwardly projecting U-shaped bracket adjacent one end thereof, a movable jaw arranged co-extensively therewith and having a portion thereof disposed between the upset legs of the bracket and pivotally connected thereto, a link pivotally connected to the stationary jaw adjacent the end thereof, remote to the bracket, and in which the complementary end of the movable jaw is loosely disposed, a lever pivotally connected at one of its ends to said link, and said lever being provided with a cam portion disposed eccentrically to its pivot 20 for engaging and moving the movable jaw toward the stationary jaw.

2. A nut cracker comprising an elongated stationary jaw, a movable jaw disposed thereabove and arranged substantially coextensively therewith, said jaws being pivotally connected adjacent corresponding ends thereof, a link pivotally connected to the stationary jaw, adjacent its opposite end and in which the complementary, opposite end of the movable jaw is loosely disposed, 30 and a lever pivotally connected, adjacent one of its ends, to the link, and provided with an eccentric portion for engaging the upper side of the last mentioned end of the movable jaw, for swinging said movable jaw end toward the complementary end of the fixed jaw, when the lever is swung in one direction, said lever having two independent swinging movements relatively to the jaws.

WILLIE E. PRICER.
